UNITED STATES PATENT OFFICE.

JOHN D. MACLACHLAN, OF DETROIT, MICHIGAN, ASSIGNOR OF ONE-HALF TO GEORGE W. GOLDEN, OF DETROIT, MICHIGAN.

AUTOMATIC REGULATING MEANS FOR FEEDING WATER TO FLASH-BOILERS.

No. 922,790.

Specification of Letters Patent.

Patented May 25, 1909.

Application filed July 1, 1907. Serial No. 381,761.

To all whom it may concern:

Be it known that I, JOHN D. MACLACHLAN, a citizen of the United States, residing at Detroit, in the county of Wayne and State of Michigan, have invented certain new and useful Improvements in Automatic Regulating Means for Feeding Water to Flash-Boilers; and I do hereby declare the following to be a full, clear, and exact description of the invention, such as will enable others skilled in the art to which it appertains to make and use the same.

My invention relates to means for automatically regulating the feed of water to flash steam boilers.

One object is the provision of a construction which may be applied to the piping system of any flash boiler without altering the system in any way.

A further object is the provision of a construction applicable to motor vehicles wherein the operating parts may be located in any convenient position and are not required to be situated at some definite point.

Still another object is the provision of a construction adapted to clean itself of scale or sediment.

Another object is to provide means which may be easily and quickly assembled or disassembled without changing the adjustment and in which the valve seat may be ground without removal from the system and without disconnecting the piping.

To these and other ends, my invention consists in certain novel features and combinations such as will be more fully described hereinafter and particularly set forth in the claims.

In the accompanying drawings, Figure 1 is a view showing the application of my invention to a flash steam boiler system; Fig. 2 is a vertical sectional view through the combined relief valve and air chamber; and Fig. 3 is a detail view of the valve.

(A) indicates the flash boiler; (B), the water tank or reservoir preferably open to the atmosphere; (1), the feed pipe leading from the tank to the boiler; (2), the pump connected in any suitable manner to the engine and operated at all times while the engine is running; and (3), the steam supply pipe from the boiler to the engine. The boiler is heated in any suitable manner, as by a burner (4) supplied with fuel from a pipe (5).

The operation is as follows: Assuming that

the boiler and engine are in operation, water is forced through conduit (1) to the boiler from the tank (B), in predetermined quantities. Now, it is obvious that the engine may and does require varying quantities of steam under different working conditions. For instance, when traveling up-grade, a large quantity of steam is needed, whereas when traveling on a level at slow speed with a light load, but little steam is required. And my invention is designed to automatically vary the supply of water to the boiler, it being assumed for present purposes that the quantity of steam generated from a continuous supply of water under a constant head discharged by a pipe of predetermined size is always the same. To this end, therefore, I connect the inlet arm 6 of a by-pass at some convenient point in the main conduit (1) between the pump and the boiler, such by-pass arm leading to a combined relief or by-pass valve and air-chamber. This combined relief or by-pass valve and air chamber comprises a tubular casing (7) provided with inlet and outlet ports (8) and (9), an inverted valve (10) being located between and controlling the passage of liquid from the inlet to the outlet port.

The head of the valve is provided with a kerf (11) adapted to receive a screw-driver or other suitable tool whereby the valve may be rotated on its seat (12) and with the introduction of a little emery-dust, the valve and its seat may be ground without removing or disconnecting the piping, valve-casing or air-chamber.

An air-chamber (23) of any usual form freely communicates with and forms a practically integral part of the valve casing above the inlet port (8), to which port the inlet arm 6 of the by-pass is connected. To the opposite end of the valve-casing and forming a part thereof beneath the outlet is removably secured one end of a sleeve (14), the lower end of the sleeve being closed by a screw-plug (15) adjustable relative to the sleeve and carrying a lock-nut (16) for retaining the plug at any point in its adjustment. Within the sleeve is located a rod (17), one end of which is received in a recess (18) in the plug (15), the opposite end of the rod being provided with a conical head (19) received in a conical recess (20) in the valve head. A spring (21) encircles the rod, the lower end of the spring abutting the inner end of the

plug, the opposite end of the spring bearing against the head (19) of the rod. By adjusting the plug relative to the sleeve the spring is made to bear more or less firmly 5 against the head of the rod and the valve to hold the latter on its seat. The recess in the plug is of such length as to permit the plug to be adjusted relative to the rod. The return pipe or discharge arm 22 of the by-pass leads 10 from the outlet port (9) back to the reservoir.

The operation of my device is as follows: Assuming that the engine is running, the pump draws water from the reservoir and delivers it to the boiler through pipe (1). 15 Now, in case the engine is able to use all the steam supplied to it, such action will continue, but in the event that a greater quantity of steam is generated than can be used by the engine, the excess steam will 20 create a back pressure against the water in pipe (1) causing the entire quantity of water or a proportion thereof to find its way along the by-pass pipe (6) and through port (8) into the relief valve-chamber where it presses 25 against the valve (10). Now, if the pressure of the water against the valve is strong enough, the water will unseat the valve against the tension of spring (21) and find its way back to the reservoir through port (9) 30 and return pipe (22). As soon as the steam pressure drops, the back pressure will be reduced, the valve will seat, and the water will resume its regular course through pipe (1) to the boiler. Thus the requirement of the 35 engine, or more specifically the load or work to be done, automatically controls the supply of feed-water to the boiler.

The sleeve (14) with the rod (17) and spring (21) can be removed and the valve 40 (10) taken out, replaced or ground without disassembling the piping or changing the adjustment.

The relief valve and air-chamber can be located at any convenient point on the vehicle, even on the dash if desired, and the invention can be easily applied to any flash boiler.

The function of the air-chamber (23) is to prevent water-hammer in pipe (6) when the 50 valve (10) suddenly closes. The air-chamber operates to preserve an elastic or yielding pressure upon the water admitted thereto from the by-pass pipe, so that the valve (12) is practically balanced between the spring 55 pressure below and the air-pressure on the

water above, thereby insuring the quiet and easy opening and closing of the valve.

The device is self-cleaning, the valve being inverted so that any dirt or sediment entering the valve-chamber will pass the valve 60 without clogging.

Having thus fully disclosed my invention, what I claim as new is—

1. In a device of the character set forth, the combination with a generator, a reservoir, a feed pipe directly connecting the generator and reservoir and a pump in the feed pipe, of a bypass leading from the feed pipe at a point intermediate the pump and generator, an air chamber, the open end of 65 which terminates in a valve casing provided with inlet and outlet ports, a valve and valve seat located between the ports, the bypass arms communicating with the inlet and outlet ports respectively, and means for 70 yieldingly maintaining the valve on its seat. 75

2. In a device of the character set forth, the combination with a bypass, of an air chamber, the open end of which terminates in a valve casing having inlet and outlet 80 ports, a valve and valve seat located between the ports, a hollow sleeve extending from the opposite end of the valve casing, a spring-actuated headed rod received in the sleeve, one end of the rod engaging the 85 valve, a socketed plug adjustable on the sleeve, the opposite end of the rod receivable in the socket in the plug and a lock nut on the plug, the nut engaging the sleeve to 90 maintain the plug in adjusted position. 95

3. In a device of the character described, the combination with a boiler, a reservoir, a single valveless feed pipe connecting the boiler and reservoir, and a pump in the feed pipe, of a bypass leading from the feed pipe 95 at a point intermediate the pump and boiler, an air chamber, the open end of which terminates in a valve casing, having inlet and outlet ports, a valve and valve seat located intermediate the ports, and yielding means 100 for retaining the valve on its seat, the air chamber and its associated parts located intermediate the ends of the bypass.

In testimony whereof, I affix my signature in presence of two witnesses.

JOHN D. MACLACHLAN.
